UNITED STATES PATENT OFFICE.

TEMPEL L. KINNE, OF DALLAS, TEXAS, ASSIGNOR TO THE MURRAY COMPANY, OF DALLAS, TEXAS, A CORPORATION OF TEXAS.

BOLL BREAKER AND CLEANER.

1,186,798.

Specification of Letters Patent. Patented June 13, 1916.

Application filed April 1, 1915. Serial No. 18,629.

To all whom it may concern:

Be it known that I, TEMPEL L. KINNE, a citizen of the United States, residing at Dallas, in the county of Dallas and State of Texas, have invented certain new and useful Improvements in Boll Breakers and Cleaners, of which the following is a specification.

My invention has relation to an improved means for handling and cleaning seed cotton prior to its presentation to the gins and in such connection it relates more particularly to the construction and arrangement of the apparatus constituting such means.

Heretofore in the handling of cotton during transit from the wagon to the gins under pneumatic pressure or suction it was customary to send the cotton first through a boll breaker (if required) and a cleaning mechanism and thereafter to convey the cleaned cotton to the gins in either of two ways,—namely, by means of a belt conveyer or by a pneumatic conveyer. Where boll breaking as well as cleaning are necessary it is usual to combine the two instrumentalities in one apparatus, the two mechanisms being inclosed in one housing. If, after the cleaning operation, a belt conveyer was used to convey the cotton to the gins, it was necessary to separate the air from the cotton prior to the delivery of the cotton onto the conveyer. The air separating means was usually located some distance from the boll breaker and cotton cleaning apparatus, and operated after the cotton left the apparatus.

Some attempts have been made to combine in the breaking and cleaning apparatus, a means for separating the air from the cotton prior to the discharge of the cotton from the apparatus. So far as I am aware, however, the air separating means was extraneous to the cleaning chamber and depended upon the use of the cleaning screen of said chamber as the air separating means. It will be obvious to those skilled in the art that all such attempts to include in the cleaning apparatus, an air separating means extraneous to the screened cleaning chamber and which requires the coöperation of the cleaning screen to separate the air from the cotton, must of necessity result in total or partial failure by reason of the fact that the passage of the air, through the screen, sheets the cotton flat upon the screen and thus impedes not

only the air separating but also the cleaning operations. The operation of the beating or agitating fingers of the cleaner will partly remove the sheeted cotton but only in the form of stringy, broken sample. These certain disadvantages in the use of the aforementioned instrumentalities and means are augmented by the main disadvantage arising from the excessive cost of construction and maintenance of what may be termed intricate and complicated structures and it is the principal object of my present invention to obviate all these disadvantages by providing an apparatus or structure wherein,—

First: The boll breaking and cotton cleaning apparatus is so constructed and arranged that it combines in the one structure not only the function of boll breaking and cotton cleaning but also the additional function of air separation whereby the cotton may be discharged from the apparatus direct to the belt conveyer without the intervention of an air separating means extraneous to the cotton cleaning chamber. In my apparatus the function of air separation is performed by the escape of air toward the longitudinal axis of the apparatus or centripetally, whereas the functions of breaking and cleaning are performed peripherally or centrifugally in the apparatus.

Second: The boll breaker and cotton cleaner are so constructed and arranged that the apparatus may be used to perform both functions to their fullest extent, or to perform the boll breaking function to a modified extent and the cotton cleaning function to its fullest extent or to perform the cleaning function to its fullest or to a more or less moderate extent irrespective of the boll breaker which is not functionally in use. The advantage of such adaptability of the apparatus will be understood when it is recalled that, in certain cotton growing localities, a boll breaker is not required as the cotton is free and not bolly. In other localities however both breaking and cleaning operations must be performed on the cotton. My improved apparatus may be installed in any locality to be used for any or all grades or classes of cotton by very simple regulation of the apparatus.

A secondary object of my invention is to

provide an outlet or discharge for the cotton from the apparatus, said outlet for the cotton being at the periphery of the cleaning chamber and the outlet for the air being axially of the apparatus.

The nature and scope of my invention will be more fully understood from the following description taken in connection with the accompanying drawings forming part hereof, in which,—

Fig. 1, is a top or plan view of a boll breaker and cleaner embodying main features of my invention and installed in operative position upon the gin stands. Fig. 2, is a longitudinal sectional view of the boll breaker and cleaner. Fig. 3, is a cross-sectional view of the boll breaker and cleaner the section being taken on line $x-x$ of Fig. 2. Fig. 4, is a cross-sectional view taken on line $y-y$, of Fig. 2. Fig. 5, is a cross-sectional view taken on line $z-z$ of Fig. 2. Fig. 6, is a top view of the apparatus with the entrance end broken away and sectioned to illustrate the means for adjusting the inlet to the apparatus. Figs. 7 and 8 are end elevational views illustrating modified forms of connecting the discharge from the cleaner to the belt distributor, and Fig. 9, is a side elevational view illustrating the valve controlling the main inlet and the overflow inlet to the apparatus.

Referring to the drawings 1 represents the external frame for the apparatus which for convenience in manufacture and the assembly of parts is preferably substantially pentagonal in cross section with the point of the pentagon pointing downward to form a trash trough 2 wherein a trash conveyer 3 of any well known construction is designed to operate. At preferably the inlet end of the apparatus this trough 2 discharges into a pipe 4 having its exterior end closed by a collapsible valve 5 also of well known form. The outside frame or casing 1 is built up of alternate wood and metal parts—the metal being preferably sheet iron or steel—and form essentially an air tight compartment or chamber.

Within the casing 1 and supported therein in any suitable manner is a tubular wall or casing 6 extending longitudinally from end to end of the apparatus. Inside the chamber within the tubular casing 6 is arranged the boll breaking and cleaning mechanism. This mechanism comprises essentially a shaft 7 traversing the apparatus and having bearing 8, 8 on the exterior of the casing 1. To the shaft 7, which is driven in any suitable manner, is secured at intervals a series of frames or spiders 9 to the ends of the arms 10 of which are secured the wall 11 of a hollow drum 12. For convenience of construction this wall is shown as a six sided polygon but it may be of any polygonal shape or cylindrical. The wall 11 is made

preferably of sheet metal and is provided with a series of perforations. Beyond the wall of the drum extend the breaker paddles or fingers 13 and the cleaning and stirring fingers or paddles 14 both being, as illustrated, of well known construction and arrangement. At the inlet or boll breaking end of the apparatus the fingers or paddles 13 coöperate with a breast 15 of preferably slatted construction and this breast 15 forms a portion of the lower part of the tubular casing 6. A breast regulating device 16 as shown in Fig. 3 serves to bring the breast 15 closer to the paddles 13 or to bring said breast and said paddles a farther distance apart as occasion requires.

At the cleaning part of the apparatus the fingers 14 coöperate with a screen 17 forming the lower part of the tubular casing 6. The screen 17 is approximately circular and extends longitudinally from where the breast 15 terminates to the outlet end of the apparatus.

The inlet to the apparatus comprises a box like structure 18 supported on the top of the external casing 1 and substantially fan shaped in top plan view. The broad base of the fan discharges downwardly into the casing 1, the opening 19 from the box 18 extending longitudinally so as to cover the entire boll breaking portion of the apparatus and substantially the major portion of the cleaning portion of the apparatus. The contracted mouth 20 forming the entrance to the box like inlet 18 communicates directly with a chute or flue 21 and said chute 21 is provided with means whereby it may be shifted in the box 18 in a direction longitudinally of the apparatus so that the chute 21 may connect the mouth 20 with any portion of the discharge 19 from box 18. In this manner cotton and air introduced through mouth 20 are directed by the chute 21 to the proper point in the apparatus which point is determined by the quality of the cotton. Thus if the cotton is bolly the chute 21 directs the discharge of air and cotton to the boll breaking fingers 13 so as to bring all or a portion of the boll breaker initially into operation.

If the cotton is free then chute 21 may be turned to direct the air and cotton from mouth 20 to a point beyond the boll breaker so that the cotton may be subjected by the fingers 14 to a cleaning operation without passing through the boll breaker. In assembling the parts so that the chute 21 may be swung in box 18, a preferred form of construction and arrangement is illustrated in Fig. 6. Broadly considered, the front end of chute 21 is hinged as at 22 to mouth 20 and a rack 23 and pinion 24 controlled by a hand wheel 25 may be used to shift the chute 21 as indicated in dotted lines in said Fig. 2.

The outlet 26 for cotton from the appa-

ratus is at the periphery of the casing 27 and terminates in a chute 28 leading downward to the belt distributor 29. The connection between the base of chute 28 and the top of belt distributor 29 should by preference be provided with a valve to prevent air from passing to or from the apparatus through chute 28 when the belt distributor itself has no valves. In Fig. 7 the valve is 10 in the form of a paddle wheel 30 the blades of the wheel having india rubber or leather flaps 21. In Fig. 8, the valve is collapsible canvas pocket 32^a of the ordinary well known type.

15 The outlet 32 for air from the apparatus is axially located at the discharge end of the apparatus and the wall of outlet 32 forms a continuation of the wall of the hollow drum as clearly shown in Fig. 2. 20 The outlet 32 enters an air box 33 having an outlet pipe 33^a projecting beyond the casing 1 of the apparatus and connected by pipe 34 with the suction fan 35 (see Fig. 1).

In the operation of the apparatus, the 25 cotton under air pressure is introduced into the apparatus and delivered to the exterior of the hollow drum 12 and between the drum and the casing 6. If the cotton and air are directed by chute 21 to the boll breaker fingers 13 then the first action of the apparatus is to break the bolls as well as to permit of portions of the air escaping into the interior of the drum 12 through the perforations in the wall 11 of said drum. 30 The cotton next passes into the cleaning portion of the apparatus wherein it is stirred by the fingers 14 and the dirt extracted through the screen section of casing 6. During this cleaning operation the 35 remainder of the air separates from the cotton and enters through perforated wall 11 into the interior of drum 12. The separation of the air is assisted by the centrifugal action of the revolving drum 12 which prevents the cotton clinging to the wall 11 of the drum but does not prevent but rather assists the ready passage of the air to the interior of the drum 12.

The cotton whether it is to be treated by 40 boll breaker and cleaner mechanisms confined in whole or with part only of the breaker included, or is to be treated by the cleaning mechanism in whole or part with the boll breaker mechanism excluded is always subjected to centrifugal action and the 45 cleaning and breaking is performed extraneous to the hollow drum which forms the conduit for the passage of the air centrally or axially of the apparatus. The outlet 50 26 for the cotton at the discharge end of the apparatus is arranged centrifugally of the apparatus whereas the outlet 32 for the

air is arranged axially or centripetally of the same.

In case of overflow from the belt distributor, a suction pipe 40 is used to convey the overflow to the mouth 20 and to discharge it through a fixed chute 41 directly to the cleaning fingers 14 at a point near the outlet end of the apparatus.

Having thus described the nature and objects of my invention what I claim as new and desire to secure by Letters Patent, is,—

1. In a device of the character described, 75 a boll breaking mechanism and a cleaning mechanism arranged to operate successively upon the cotton combined with means for feeding the cotton to a predetermined point intermediate of the beginning of the boll 80 breaking and the end of the cleaning mechanisms.

2. In a device of the character described, 85 a cleaning mechanism and an air separating means combined in one structure, said cleaning mechanism consisting of a revoluble hollow drum, a series of paddles projecting beyond the periphery of said drum and a screen casing inclosing the drum and fingers, 90 said paddles coöperating with the screen to clean the cotton centrifugally of the drum, and a perforated wall for the drum constituting the air separating means to permit of the escape of the air axially of the device.

3. In a device of the character described, 95 a boll breaking mechanism, a cotton cleaning mechanism and an air separating means combined in one structure, said boll breaking mechanism and cotton cleaning mechanism consisting of a revoluble hollow drum, a 100 double series of paddles projecting beyond the periphery of the drum, a casing inclosing the drum and fingers, a breast formed on one portion of the casing and a screen surface formed on the remaining 105 portion of said casing, said paddles coöperating with the breast and with the screen to break the bolls and screen the cotton centrifugally of the drum and a perforated wall for said drum constituting the air separating 110 means to permit the escape of air axially of the device.

4. In a device of the character described, 115 a boll breaking and a cotton cleaning mechanism arranged to operate successively upon the cotton, combined with an inlet for the cotton comprising essentially a chute and a means for directing the chute to varying points intermediate of the ends of the said boll breaking and cleaning mechanisms.

In testimony whereof I have signed my name to this specification.

TEMPEL L. KINNE.
